2,395,942

VALVE

Thomas F. Saffady, Detroit, Mich.

Application September 10, 1945, Serial No. 615,342

3 Claims. (Cl. 123—177)

The object of my invention is to provide a more efficient valve of the liquid cooled type.

Still a further object of my invention is to provide a liquid cooled valve wherein there is means for insuring complete wetting of the interior of the valve head, especially adjacent to the valve seat portion thereof.

Still a further object of my invention is to provide a hollow valve which is partly full of liquid coolant which has a hollow stem and a hollow tulip shaped head and to provide in connection with the head and stem a member which tends to deflect the coolant toward the periphery of the head and which also acts to increase the normal speed of the coolant so projected to increase the efficiency of the cooling fluid.

With these and other objects in view, my invention consists of the construction claimed in the claims, described in the specification and shown in the accompanying drawing, in which:

Figure 1 shows a side elevation of the improved valve, parts being broken away to better illustrate the construction.

Figure 2 shows a top or plan view of the valve.

Figure 3 shows a horizontal section on the line 3—3 of Figure 1.

Referring to the accompanying drawing, a hollow stem 10 has a hardened tip 11, which is designed to cooperate with a cam or tappet not shown. At the opposite end of the stem a tulip 12 is formed in any suitable manner but preferably by preforming and then welding it to the stem. A cap or head member 13 is secured to the tulip 12, preferably by providing the locating shoulder 14 and the flush weld 15. This insures the proper positioning of the head 13 and a clean surface on the inside and outside thereof.

A member 16 is either formed integrally with or welded to the inside of the head 13 at the center thereof. This weld is indicated by the dotted line 19. The base portion of the member 16 is flared outwardly as shown at 17 and the contracted tip portion 18 thereof extends a substantial distance into the top of the stem 10. The effect of this member 16 is first to cause a Venturi action of the liquid which is forced past the tip 18. It will be understood that these valves are normally charged with metallic sodium in an amount about 60 per cent of the total space inside the valves. When the engine is at rest, the sodium solidifies, but when the engine is working, the valve temperature raises sufficiently to liquefy the metallic sodium so that as the valve reciprocates rapidly during the operation of the engine the sodium is first forced toward one end of the

valve and then the other end. As this reciprocation is very rapid, the sodium must circulate very rapidly and contact the entire surface on the inside of the valve with each reciprocation. As the valve reaches the top limit of its movement, the sodium goes to the bottom of the valve. When the valve returns to its normal position the sodium is forced up to the top of the valve. As the valve is only partially filled with the liquid there is some tendency for the sodium to form vapor locks due to the extremely high speed of the reciprocation. It was heretofore proposed to contact the top of the valve stem to reduce its diameter and thereby secure this Venturi effect. If the stem material is merely beaded inwardly, then the ultimate strength of the stem is lessened. If the stem is thickened to form this venturi, then either expensive machining operations or expensive forming operations are necessary. With my improved structure the member 16 may be very simply and inexpensively forged and then welded into place before the head is welded to the valve or, of course, the entire head 13 and member 16 may be forged in one piece. I have found that if the tip 18 is made to have a cross section of approximately one quarter that of the stem interior, that the most efficient results are secured. My improved structure has the further advantage of having the flared base 17 which directs the fluid accelerated by the venturi formed by the tip 18 directly toward the periphery of the interior of the head of the valve. Naturally this is part of the valve which is the most critical to cool.

Some changes may be made in the arrangement and construction of my improved valve, and it is my intention to cover by my claims such changes as may reasonably be included within the scope thereof.

I claim as my invention:

1. In a tulip shape valve for internal combustion engines, a hollow stem sealed at one end, a hollow tulip head connected to the other end of the stem, the stem being partly filled with a cooling substance, a cap closing the open end of the tulip, said cap being welded to the tulip, and a combined deflector and Venturi member extended downwardly from the cap to form with the stem a Venturi restriction and to deflect the cooling substance as it enters the head toward the periphery of the tulip.
2. In a tulip shape valve for internal combustion engines, a hollow stem sealed at one end, a hollow tulip head connected to the open end of the stem, the stem being partly filled with a cooling substance, a cap closing the open end of

the tulip head, the cap and tulip having inter-engaging surfaces to positively determine the position of the cap relative to the tulip and the parts being welded together, and a combined deflector and Venturi member extended downwardly from the cap to form with the stem a Venturi restriction and to deflect the cooling substance as it enters the head toward the periphery of the tulip.

3. In a tulip-shape valve for internal-combus-

tion engines, a hollow stem sealed at one end, a hollow tulip head connected to the open end of the stem, the stem being partly filled with a cooling substance, a cap closing the open end of the tulip and a combined deflector and Venturi member secured to the inside of the cap and having a flared base to deflect cooling substance toward the periphery of the valve and a tip to form with the stem a venturi.

THOMAS F. SAFFADY.
